Attorneys.*

UNITED STATES PATENT OFFICE.

ROSCOE F. WARREN, OF LOS ANGELES, CALIFORNIA.

RIFLE-STOCK-BUTT, CARTRIDGE BELT AND COUNTERSUNK RIFLE-SLING LOOP.

Application filed December 15, 1927. Serial No. 240,173.

My invention pertains to a rifle stock butt cartridge belt and counter-sunk rifle sling loops.

An object of my invention is attachments 5 to a rifle whereby a reserve stock of ammunition may be carried on the side of the butt of the rifle, and also in which the sling loops to which the strap slings are attached may, when the straps are detached therefrom, be 10 housed in a counter-sunk manner on the butt and the hand guard, whereby there is no danger of these loops catching the rifle when drawing it from a holster for use, and no 15 danger of these catching on obstructions when hunting.

In constructing the holder for cartridges on the butt I preferably form a series of belt loops such as used on cartridge belts, these loops being attached to a suitable base 20 and this base is attached to the butt of the rifle. Therefore, when this additional butt belt is filled with cartridges, the hunter always has ready at hand an additional supply 25 of cartridges which may be quickly inserted in the rifle. The counter-sunk sling loops are preferably pivotally mounted on blocks and these blocks are inserted in recesses in the butt stock and in the hand guard, there 30 being grooves to receive the loops when swung into position to be flush with the surface of the butt stock and the hand guard.

My invention will be more readily understood from the following description and drawings, in which:

35 Figure 1 is a side elevation of a rifle showing the butt cartridge belt and the sling loops in their extended position.

Fig. 2 is a perspective view of the butt cartridge belt partly broken away to show 40 the manner of attaching.

Fig. 3 is a face view of one of the sling loops.

Fig. 4 is a sectional view of a sling loop taken on the line 4—4 of Fig. 3.

45 Fig. 5 is a perspective view of the block holding the loop removed.

In the drawings, the rifle stock butt is indicated generally by the numeral 11, and this has a shallow recess 12 on one side. In this 50 recess is fitted a base 13, such base having a series of loops 14 preferably formed of leather and secured to the base by stitches 15 at the edge and stitches 16 between the loops, thereby leaving a series of parallel 55 pockets 17 in which cartridges may be in-

serted. I find it of advantage to form the base of a relatively hard leather and the loops of somewhat softer leather. The base is secured in the recess 12 by glue or cement, or if desired, by screws, and thereby holds 60 the loops having the pockets rigidly secured to the stock butt. The cartridges 18 are preferably inserted as illustrated with the points towards the muzzle of the rifle.

It will be readily seen from the above 65 construction that cartridges may be readily and quickly extracted from the pockets and inserted in the rifle for shooting, and the hunter could do this much more rapidly than he could draw the cartridges from a belt. 70 This, in addition, also affords a safe manner of carrying the cartridges while hunting, as by this construction, if desired, the hunter may have his rifle unloaded and therefore 75 there would be no danger of a premature shot, and, as the cartridges are so conveniently placed in regard to the chamber, this latter can be quickly loaded.

The sling loops and their attachment is 80 substantially as follows:

In Fig. 1 the hand guard is designated by the numeral 20 and both the hand guard and the stock butt have a rectilinear recess 21, and in this recess there is inserted a block 22, being retained therein by screws 85 23. The block has a transverse opening 24 therethrough to which is secured a loop 25 by a pivot pin 26. On each side of the block in the stock butt and in the hand guard there are a pair of grooves 27 adjacent the opposite sides of the block 22 and in the block there is a transverse groove 28 which joins the grooves 27. The loop may, therefore, be pressed into the grooves 27 and 28 and when housed in such position leaves a flush 90 surface at the hand guard, and at the lower edge of the stock butt, preventing the loop from catching on the holster when withdrawing the rifle therefrom, or from catching on obstacles when hunting; it being, of 95 course, understood that when the loops are housed in the manner above described that the strap 29 of the sling is removed.

In the construction of the counter-sunk rifle sling loops it is desirable that they 100 have a certain frictional motion in regard to the pivot pin 26 so that when the loop is properly housed in the grooves 27 and 28 it does not tend to shift out of the grooves into the position shown in Figs. 3, 4 and 5. 110

An important feature of the stock butt cartridge belt is that when the gun is put away in camp there is always the particular ammunition which fits the gun always with 5 the gun, so that it is ready for practically instant use. In addition to this, it has been found that in big game hunting fatalities and accidents usually happen by the hunter in his excitement emptying the magazine of 10 cartridges, and consequently when attacked by dangerous game does not have sufficient ammunition to save himself. But with the stock butt cartridge belt the hunter, while keeping the magazine full, can use the rifle 15 as a single loader, taking the cartridges from the stock belt so that in cases of emergency he has the full magazine to rely on.

Various changes may be made in the principles of my invention without depart-

ing from the spirit thereof, as set forth in 20 the description, drawings and claim.

I claim:

In the art described, a gun having a stock butt with a shallow recess on one side, a base formed of leather, a strip of flexible 25 material formed into a series of parallel loops, the ends of said material being stitched to the leather base and said material between adjacent loops being stitched to said base, the loops in the base forming a 30 series of parallel open ended pockets adapted to hold cartridges, and said base being inserted in the recess and secured therein.

In testimony whereof I have signed my 35 name to this specification.

ROSCOE F. WARREN.
